FRANK CARTLIDGE, OF CINCINNATI, OHIO, ASSIGNOR TO SULLIVAN MACHINERY COMPANY, A CORPORATION OF MASSACHUSETTS

MINING APPARATUS

Application filed August 10, 1922. Serial No. 580,907.

The present invention relates to an apparatus for mining coal and possibly other similarly located deposits and more particularly to an apparatus of this type employed for undercutting a body of coal prior to the breaking down of the coal in the usual manner.

In mining a vein of coal it is the usual practice to first undercut the block of coal to the desired depth, this cut extending across the vein throughout the width of the room, and to thereafter break down the thus undercut block by a blasting or wedging operation. In present day practice, the undercutting of the coal is accomplished by the use of mining machines which form a horizontal cut of uniform width, extending inwardly from the breast of the vein to a depth of six feet or thereabouts. These mining machines consist essentially of a series of cutting members supported upon a carrier chain movable over a cutter bar, which is traversed across the width of the vein to progressively undercut the coal from one side of the room to the other. The disadvantage of undercutting the coal in this manner is due to the fact that upon breakdown the mass of coal merely drops a distance approximately the width of the undercut and must be laboriously removed from this position either manually or by some form of mechanical loader. It is desirable in mining bituminous coal that it shall be broken down in comparatively large lumps with a substantial freedom from slack and when the block of coal is broken down in this manner the disadvantages of the foregoing method of undercutting are even greater than otherwise. It is the object of the present invention to provide a new and improved form of apparatus for undercutting the coal in such a manner that upon the subsequent breaking down of the thus undercut coal the mass of coal will be pitched out or ejected into a position where it may be conveniently loaded into the usual mine cars.

With this object in view, one feature of the invention contemplates the provision of a series of cutting members so designed and arranged that two undercut slots or kerfs are formed in the coal which converge from the

breast of the coal toward a meeting point located at approximately the rear extremity of the block to be broken down. The formation of converging undercuts in this manner provides a V-shaped opening or recess beneath the block of coal so designed that upon breaking down the undercut block the mass of coal is pitched forward onto the floor of the room in a convenient position for loading.

A further feature of the invention consists in the combination of a supporting bar movable across the vein of coal and carrying a series of cutting members which are guided to move inwardly from the breast of the vein of coal to the rear portion of the cut and thence outwardly returning to the breast of the vein and cutting upon both the inward and outward movements. With this construction it will be evident that a single traverse of the cutter bar forms two intersecting slots in the body of the coal and completely separates a wedge shaped slab which on removal leaves a V-shaped opening. The underside of the slot is substantially horizontal and forms a continuation of the floor of the room and the upper side of the slot slopes from the rear edge of the block to be disengaged upwardly toward the breast of the coal, with a sufficient slope to pitch forwardly into the room when the latter is broken down.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention Fig. 1 represents a plan view of the new form of mining machine; Fig. 2 is a side elevation of the machine shown in Fig. 1 with the mass of coal subjected to the cutting operation shown in section; Fig. 3 is an elevation partly in section of the rear end of the cutting mechanism; Fig. 4 is a section upon the line 4-4 of Fig. 3 showing the turret for supporting the cutter bar together with the operating mechanism therefor; Fig. 5 is a detail

illustrating the construction of the cutting mechanism at the point where the slots intersect; Fig. 6 is a cross section of the cutting mechanism upon the line 6-6 of Fig. 5; and 5 Figs. 7 and 8 are diagrammatic views illustrating one method of forming the undercut slot or kerf in the body of coal to be broken down.

The illustrated embodiment of the invention shows a body or carriage 10 enclosing a drive motor 12. This motor serves to operate a ring gear 16 through an intermeshing miter gear 17 for actuating the cutting members and in addition operates a feed operating member herein a chain pulley 20 located in the rear end of the carriage through a suitable clutch indicated at 22 and change speed gearing indicated at 24. The shaft 14 is directly connected to the upper portion of 15 a rotatable turret 26 which is supported upon a shoe 28 underlying the body 10 and is journaled for rotation in a circular guideway 29 secured to the shoe through fastening members 31. This turret is provided with a bearing box 30 extending therefrom, as shown in Fig. 3, which constitutes the support for a cutter bar, indicated generally at 32, this cutter bar being provided with a hollow bearing member 34, which is slidingly received 20 upon the box 30 and is adjustable with relation thereto through a threaded member 36. It will be evident that with this construction the rotation of the turret serves to sweep the 25 projecting cutter bar in a circular path, which is concentric with the axis of the turret shaft 14. Projecting upwardly from the cutter bar adjacent the outer periphery of a stationary head 40 overlying the turret is a drag member 42 which is provided with a curved shoe 44 received within a circular track 46 formed in the periphery of the head 40. This drag member 42 is provided with a transverse slot 48 which receives an operating chain of usual form, the latter being connected to the drag 30 member through a pin 50 which may be dropped through one of the links of the chain. The operating chain for revolving the turret and for traversing the mining machine bodily across the vein of coal is indicated at 52 and is driven from the drive pulley 20, the chain passing at opposite sides of the drive pulley over guide pulleys 54 and 56 and extending in opposite directions from the 35 opposite ends of the machine body 10. The general mode of operation of the mining machine will be evident from an inspection of Fig. 1 taken in conjunction with Figs. 7 and 8. When it is desired to initiate the undercutting of the coal body one end of the operating chain is connected to the drag member 42 and the opposite portion of the chain passes over the drive pulley 20 and the guide pulleys 54 and 56. Thereafter the rotation 40 of the chain pulley with a consequence fore-

shortening of the chain serves to sweep the cutter bar through an arc, as indicated, causing the cutting members to enter into the body of coal. When this initial arc has been completed, the end of the chain is disconnected from the drag member 42 and the latter is connected to the stationary head 46 through a pin 60 which passes through the shoe 44 and the flanges of the guideway 46. The chain is then passed about a guide pulley 62 and the advance and receding portions thereof are extended in opposite directions from the opposite ends of the machine body, the free ends of the chain being connected to fixed points extraneous of the machine, as indicated in Fig. 8. Thereafter the rotation of the chain pulley causes the mining machine to be traversed bodily across the vein of coal. At the completion of this traversing movement, the cutter bar may be swung in an arc, if so desired, or the mining machine may be bodily drawn rearwardly, after the slab cut has been removed to remove the cutter bar from the slot. This general method of traversing the mining machine across the body of coal and for swinging the cutter bar in an arc with relation to the mining machine is well known to those skilled in the art and in consequence has been only briefly described herein.

According to the present invention the formation of the V-shaped slot or opening in the coal is accomplished by a chain cutter which is guided in the desired path on the cutter bar. As disclosed in the illustrated embodiment of the invention, the cutter bar is provided upon its side face with a guideway consisting of two straight portions converging toward one another and connected at the outer end of the cutter bar by a curved track or guideway through which the chain may pass freely. The location and design of the cutting chain is such that a traversing movement of the cutter bar causes the chain to cut throughout both portions of its travel to form two intersecting slots or undercuts during a single movement of the cutter bar. The cutter bar 32 projects laterally from the supporting turret 26 and is provided with a continuous guideway for the passage of the cutting chain. The cutter bar, as indicated generally in Fig. 1 and Figs. 5 and 6, comprises upper and lower bars 70 and 72 which are connected at one end with the bearing member 34 and at the opposite end are connected to provide a curved portion, as indicated at 74. A cutting chain is supported upon the bar and moves in a path which conforms in contour to the skeleton frame of the bar. This chain comprises a series of links 75, each of which carries an adjustable cutting tool 77 of usual form. The links 75 are connected by intermediate links 79 and pivot pins 80. As indicated in Figs. 5 and 6, the cutting chain is retained in operative posi-

tion with relation to the cutter bar during its movement thereover by guideways formed upon the cutter bar and cooperating with guide members on the chain. Each of the links 75 is provided with a guide projection 82 having a reduced portion 84 which projects into a similarly shaped groove formed in a guide plate 86 secured to the upper and lower portions of the cutter bar. These cooperating guide members prevent movement of the cutter chain away from the side face of the cutter bar. In addition, the movements of the cutting chain are constrained by guide projections 87 also formed upon the links 75 and each having a tongue 87^a projecting beneath the overhanging edge of a guide plate 88, as indicated clearly in Fig. 6. The cutters 77 may be of the usual form and are detachably mounted in the supporting links. As indicated, successive cutters project in opposite directions to cut opposite sides of the kerf. In actual practice it will be understood that instead of two successive cutters engaging with opposite sides 25 of the kerf a series of cutters may be employed which cut throughout the entire width of the kerf. The endless cutting chain is moved lengthwise of the cutter bar by means of a driving sprocket 83, which is mounted upon a stub shaft 100 journaled transversely in the turret 26, as indicated in Figs. 3 and 4. This driving sprocket is rotated from the ring gear 16 through beveled pinions 85 and 89 and spur gears 90 and 91, 35 the second spur gear being keyed to the outer end of the stub shaft 100. It will be evident that with this construction the ring gear 16 serves to continuously rotate the driving sprocket 83 in any position of the turret, the 40 beveled pinion 89, together with the spur gears 90 and 91, being mounted upon and rotatable with the turret. The driving sprocket, as indicated clearly in the drawings, is provided with a series of oppositely 45 disposed driving teeth 92, which engage between the curved faces of driving projections 94 formed upon the cutter carrying links. In addition spaces 95 are provided at one side of the driving sprocket between the links for the reception of the guide projections 87. The provision of the oppositely disposed driving teeth formed upon the driving sprocket and embracing the intermediate links 79 of the chain serves to retain the chain 50 in the desired lateral position with relation to the sprocket.

From the foregoing description it will be evident to those skilled in the art that the traverse of the cutter bar throughout the entire width of the vein of coal serves to completely disengage a wedge shaped slab from the main body of the coal, this slab being readily removed at the completion of the operation. Owing to the construction and arrangement of the cutter chain with respect

to the supporting bar, the thrust or pressure upon the cutting members during operation does not substantially interfere with the freedom of movement of the cutting chain over the bar. In this connection it will be observed that the turning movement of the chain about the end of the bar is in a plane substantially normal to the direction of feed of the cutters and in fact the chain as a whole on both the inward and outward traverse moves in a plane normal to the direction of feed.

While it is preferred to employ the specific construction and arrangement of parts shown and described, it will be understood that this construction and arrangement is not essential except so far as specified in the claims and may be changed or modified without departing from the broader features of the invention.

The invention having been described, what is claimed is:

1. In a mining device, the combination of a carriage arranged for movement along a face to be mined, a looped cutter bar pivotally mounted on the carriage for horizontal swinging movement relative thereto and having cutting elements traversing a vertically disposed orbit having a narrow wedge-shaped portion, a cutting element carrying cutter chain mounted for movement along said cutter bar, means carried by the carriage for moving the chain along said cutter bar including elements rotating on axes which remain stationary during bar swing, means for locking the cutter bar against movement about its pivotal mounting, and means for moving the carriage along such face while the cutter bar is locked against movement and while said cutter bar and cutting chain have been introduced into such face to cut a narrow wedge-shaped kerf at the base of the mine wall.

2. In a mining apparatus, the combination of a machine body adapted to move bodily relative to the mine bottom during the cutting operation, a motor carried by said body and having its power shaft extending longitudinally of the apparatus, cutting mechanism carried by said body, said cutting mechanism including a looped cutter bar arranged edgewise with respect to the mine bottom and extending lengthwise of said body during the transverse cutting operation, and cutting means mounted for orbital movement along the margin of said cutter bar, said cutter bar comprising a horizontal bottom portion and an inclined top portion, said portions converging at an acute angle towards one another at the outer end of the bar and connected by a curve of a small radius thereby forming a V-shaped cutter frame having a central core opening, mechanism carried by said body and driven by said motor for driving said cutting mechanism to effect orbital

movement of said cutting means, and mechanism for feeding said body and cutting mechanism bodily laterally relative to the face of the material to be mined and in a path parallel therewith during the cutting operation to form a narrow V-shaped slot projecting inwardly from the face of the material and extending across the face at the base of the mine wall.

3. In a mining apparatus, a machine body adapted to move bodily over the mine bottom during the cutting operation, a motor carried by said body and having its power shaft extending longitudinally of the apparatus, cutting mechanism carried by said body and including a looped cutter bar arranged substantially parallel to a vertical plane and extending lengthwise of said body during the transverse cutting operation, said cutter bar comprising a horizontal bottom portion and an inclined top portion, said portions converging at an acute angle towards one another at the outer end of the bar and connected by a curve of a small radius thereby forming a V-shaped cutter frame having a central core opening, mechanism carried by said body and driven by said motor for driving said cutting mechanism, and mechanism for feeding said body and cutting mechanism in a substantially straight line transversely across the coal face to form a substantially V-shaped slot projecting inwardly at the face of the material at the base of the mine wall.

4. In a mining apparatus, the combination of a machine body adapted to rest upon and slide in any direction over the mine bottom, a motor carried by said body and having its power shaft extending longitudinally of the apparatus, cutting mechanism carried by said body and including a narrow looped cutter bar extending lengthwise of said body during the transverse cutting operation, and a cutter chain movable along the margin of said bar in a vertically disposed orbit and driven by said motor said cutter bar comprising a horizontal bottom portion and an inclined top portion, said portions converging at an acute angle towards one another at the outer end of the bar and connected by a curve of a small radius thereby forming a V-shaped cutter frame having a central core opening, traction means extending along the face to be mined, and mechanism carried by said body for cooperation with said traction means for moving said body along said traction means to feed said cutting mechanism transversely across the coal face to cut a narrow V-shaped kerf at the base of the mine wall.

5. In a mining apparatus, a support movable bodily along a working face during lateral cutting and carrying a motor whose axis of rotation maintains substantially the same angular relation to said face during sump-

ing and bodily movement of the support transversely across the coal face during transverse cutting, cutting mechanism pivotally supported on said support for substantially horizontal swinging movement relative to the latter and said motor and including cutting elements circulating in orbits parallel to a vertical plane, and means actuated by said motor for transmitting movement to said elements in their orbits irrespective of change in position of said orbits relative to the motor during swinging of the cutting mechanism.

6. In a mining apparatus, a machine frame slideable bodily over a mine bottom transversely across the coal face during lateral cutting and comprising a motor, cutting mechanism pivotally supported on said frame for swinging movement about a substantially vertical axis relative to said frame and to said motor and including cutting elements circulating in an orbit parallel to a vertical plane, and means for transmitting movement to said elements in their orbit irrespective of change in position thereof relative to said motor during swinging of said cutting mechanism.

7. In a mining apparatus, a machine frame slideable bodily over a mine bottom transversely across the coal face during lateral cutting and comprising a motor rotating on an axis extending at all times longitudinally of said frame, cutting mechanism carried by said frame and including a pivoted cutter bar carrying cutting elements moving in orbits parallel to vertical planes, a motor driven driving element rotatable on an axis in the same line with the bar pivot, and an actuating element for said cutting elements rotatable on an axis perpendicular to the orbits of the latter and actuated by said driving element.

8. In a mining apparatus, a machine frame slideable bodily over a mine bottom transversely across the coal face during lateral cutting and comprising a motor rotating on an axis extending at all times longitudinally of said frame, cutting mechanism carried by said frame and including a pivoted cutter bar carrying cutting elements moving in orbits parallel to vertical planes, a motor driven driving element rotatable on an axis in the same line with the bar pivot, and an actuating element for said cutting elements rotatable on an axis perpendicular to the orbits of the latter and to said bar pivot and actuated by said driving element.

9. In a mining apparatus, a support carrying a motor and movable bodily transversely across the coal face during the transverse cutting operation, a vertical looped cutter bar swingable relative to said motor on a vertical axis to cut a V-shaped inwardly tapering kerf in the face of the material to be mined at the base of the mine

- wall, a cutter chain carried by said bar, and operative driving connections between said motor and chain effective in any angular position of said bar relative to said motor.
- 5 10. In a mining apparatus, a support carrying a motor, a vertical looped cutter bar swingable relative to said motor on a vertical axis and arranged to cut a narrow wedge-shaped kerf at the base of the mine
- 10 15 wall, a cutter chain carried by said bar, operative driving connections between said motor and chain effective in any angular positions of said bar relative to said motor, and means for feeding said support and
- 15 20 cutter bar bodily laterally relative to the face of the material to be mined and in a path parallel with the face during the cutting operation to cut a kerf transversely beneath the face of the material, said feeding means being operative to effect bar swing relative to said support.
